(57) CLAIM

The ornamental design for a face covering, as shown and described.

DESCRIPTION

FIG. 1 is a front perspective view of a face covering showing our new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is a front perspective view thereof, shown worn by a person.

The broken line showing of a person in FIG. 8 depicts environmental subject matter and forms no part of the claimed design. All other broken lines depict portions of the face covering that form no part of the claimed design.

No new matter has been added.
